DRIVING GEAR FOR CONTINUOUS WORKING PHOTOGRAPHIC COPYING MACHINES

Johannes Waibler, Stuttgart, Germany, assignor to Carl Janzer, Stuttgart, Germany

Application March 23, 1937, Serial No. 132,630

In Germany April 1, 1936

4 Claims. (Cl. 271—2.4)

This invention relates to an adjustable driving gear for the continuous working of photographic copying, exposing and treatment devices having a step-by-step feed of the light-sensitive bands, paper webs, or the like to be treated.

In known devices the stepwise movement through the exposure device has preferably been effected by rollers rotated at periodic intervals according to the size of an image, against which 10 rollers the light-sensitive bands, or strips, were pressed. These, being then passed through treatment baths or the like, left the device over a further pair of rollers from which they were passed over drying apparatus, or wound on spools. 15 The periodic exposure requires a step-by-step movement, corresponding to the length of the image, through the exposure device, whereas for the further treatment or winding of the light-sensitive bands there is preferably desired a 20 movement as uniform as possible and correspondingly equal to the first movement. For controlling these movements there were necessary hitherto inconvenient intermediate gears, feed gears, couplings, and regulating devices, the operation 25 and supervision of which was difficult and which were unreliable.

The invention has for its object to obviate these difficulties and to enable an operation free from objection to be obtained when copying and 30 treating light-sensitive bands, by means of simple means which can be attended to and supervised easily.

In accordance with this invention the operation of the step-by-step feed through the exposure 35 device and the withdrawal of the band from the device is brought about by frictionally locking the rollers for the sensitized paper by means of pawl gears (ratchet wheels and pawls) and a reciprocating or oscillating transmission member as, for 40 example, levers, connecting rods or the like of which the stroke is adjustable in such a manner that the feed gearing associated with the exposure device on the forward movement and the feed gearing associated with the withdrawal 45 mechanism on the reciprocating movement provides a feed adjusted for a uniform stepwise advance and a corresponding withdrawal.

The transmission mechanism connecting the two feed gears may be constructed as an oscillating lever mechanism or, in a more simple manner, as a thrust rod which engages the gears by teeth. Advantageously the transmission member connecting together the two gears is formed by a rod which at one end thereof is connected 55 to a single rack member and at the other end to

a twin rack member, the units of which are transversely displaced as regards their plane of operation. These rack members engage with toothed wheels which are linked by pawls and transmit their movement to the ratchet wheels connected to the feed rollers for the light-sensitive bands, paper webs or the like. The reciprocating transmission member of the two feed gears is adjustably connected with its driving lever or crank as regards its throw or stroke. 5

The bands after leaving the apparatus through the withdrawal gear can be guided to a suitable further apparatus, or they may be rewound on a reel actuated, say, by a friction drive. 10

The drawing shows one form of construction 15 of this feed gear restricted to the parts necessary for the understanding of the invention.

In the drawing:

Figure 1 shows the gear as seen in side elevation; 20

Figure 2 shows an end view of the withdrawal gear viewed from the right-hand side of Figure 1;

Figure 3 shows an end view of the feed gear according to Figure 1 viewed from the left-hand side. 25

Figure 4 shows an end view of the twin rack transmission member removed from Figure 2, and

Figure 5 shows a plan view of Figure 1. 30

In the drawing like references designate the same or similar parts.

The casing 1 of the apparatus for treating the sensitized band is connected to the exposure device 2. The path of the sensitive paper or like bands through the apparatus is not shown as it may be of any suitable nature according to the treatment of the band, or bands, and according to the internal arrangement of the apparatus. The roller 3 effecting the stepwise feed through the exposure device 2 is fixed on the shaft 5 and 35 co-operates with the pivoted counter roller 4 which is pressed thereagainst by means of a weighted lever 32 or by a spring in lieu thereof. On the projecting end of the shaft 5 is loosely mounted the toothed wheel 6 at the side of which 40 is secured a spring-pressed pawl 7 which engages with the ratchet wheel 8 provided with fine teeth and secured to the shaft 5. 45

The gear wheel 6 engages the rack 9 of the connecting rod 10. The rack 9 is secured in position by means of the guide roller 11. 50

The rod 10 is connected at its other end to a twin rack member, the two units 12, 13 of which engage the gear wheels 15, 16 mounted for free rotation on the shaft 14. To each of the re- 55

spective gears 15 and 16 is secured a spring-pressed pawl, indicated at 17 for the gear 15 and at 18 for the gear 16. These pawls are arranged to cooperate with a ratchet wheel 19 fixed to the 5 shaft 14. The pawls 17, 18 are located in relatively displaced parallel planes so that they do not interfere with one another during a rocking movement. To the shaft 14 is connected the withdrawal roller 20 against which the film bands 10 are pressed by the pivotally mounted counter- 10 roller 30. A weighted lever 33, or a spring, is provided for the purpose of applying pressure to the roller 30.

The racks 12, 13 are held in their position by 15 guide rollers 21, 22. To one end of the connecting rod 10 between the two feed gears there is hingedly connected the rod 23; the other end of which is adjustably mounted on the lever 24 fixed to the shaft 21. The adjustable mounting 20 may be constituted by a sliding member 25 guided in the lever 24 and movable over a scale by means of a screw 26. The lever 24 is mounted for rotation with the shaft 27 which is connected to the drive by means of a pulley 34. The lever 25 24 controls simultaneously by a cam disc 28 and lever 35 the exposure apparatus 2.

A handle 36 is provided on the shaft 14 for working the apparatus by hand.

The bands leaving the device may, if they are 30 not to be advanced for further treatment, be wound on the spool 29, indicated in chain dotted lines, which is driven in a suitable manner by a friction gear.

The operation of the apparatus is as fol- 35 lows:—

The rod 10 is reciprocated by the lever 24 through the connecting rod 23, the stroke of which is determined by the screw 26 and, during this reciprocating movement, actuates, through 40 the rack member 9, the toothed wheel 6. This wheel, when moving in a clockwise direction, rotates, by means of the pawl 7, the ratchet wheel 8 and thus the feed roller 3 for the light-sensitive paper or the like, through a corresponding 45 distance, whereas in the other direction of movement the pawl 7 returns idly over the ratchet wheel 8. During this movement, however, the rod 10, by means of its racks 12, 13, rotates simultaneously but in opposite directions the toothed wheels 15, 16 and the ratchet pawls 17, 50 18 connected thereto.

As the pawls 17, 18 act on the common ratchet wheel 19 this is rotated in a clockwise direction both during the forward and the backward movement of the rod 10 by reason of the oppositely moving ratchet pawls 17, 18 locking in one direction of movement and running freely in the other. The intermittent feed movement produced by the rack 9 is thus duplicated when the

toothed wheels 6, 15, 16 are of the same size and is converted into a corresponding continuous, or practically continuous motion.

By suitably relating the diameters of the feed roller 3 and the withdrawal roller 20, or the 5 transmission ratios between the engaging rack members, the lengths of unrolling or feed are so proportioned that during a complete feed movement the light-sensitive paper bands are moved by both gears through the same distance corre- 10 sponding to the predetermined adjustment.

What I claim is:—

1. A feeding mechanism for use in connection with photographic apparatus of the type wherein a sensitized strip is first exposed and then fed 15 through a tank for subsequent treatment, said feeding mechanism including an intermittent feeding means arranged immediately beyond the place of exposure and a continuous feeding means arranged for the delivery of the strip from 20 and beyond the treating tank, the intermittent feeding means feeding the strip from a point beyond the exposure area in the direction of strip movement into the tank and the continuous feeding means delivering the strip after 25 treatment in the tank and in the direction of strip movement, whereby the intermittent feeding means constitutes the initial strip feeding and the continuous feeding means constitutes the final strip feeding, a rod connecting and synchronizing the intermittent and continuous feeds, and a power driven drive bar reciprocating the rod to compel coordinated operations of the respective feeds on the strip.

2. A construction as defined in claim 1, where- 35 in the respective feeding mechanisms include pressure controlled rollers between which the strip is moved, a ratchet for operatively actuating the rollers of each feed, means at one end of the rod for operating the ratchet of the inter- 40 mittent feed in movement of the rod in one direction only, and means at the opposite end of the rod for actuating the ratchet of the continuous feed in both reciprocating movements of the rod.

3. A construction as defined in claim 1, where- 45 in the drive bar is connected for adjustment relative to its power connection to thereby vary the throw of the rod and correspondingly vary the linear degree of strip feed of the intermittent feeding means and the continuous feeding means.

4. A construction as defined in claim 1, where- 55 in the respective intermittent feeding means and continuous feeding means are arranged to compel the same linear travel of the strip in any one complete operation of the respective feeding means under a complete reciprocating movement of the rod.

JOHANNES WAIBLER.
